UNITED STATES PATENT OFFICE.

WILLIAM D. SLATER, OF SPRINGFIELD, MASSACHUSETTS, ASSIGNOR TO UNITED STATES ENVELOPPE COMPANY, OF SPRINGFIELD, MASSACHUSETTS, A CORPORATION OF MAINE.

ENVELOP-MACHINE.

No. 893,105.

Specification of Letters Patent. Patented July 14, 1908.

Application filed July 6, 1903. Serial No. 164,349.

To all whom it may concern:

Be it known that I, WILLIAM D. SLATER, a citizen of the United States, residing at Springfield, in the county of Hampden and Commonwealth of Massachusetts, have invented a new and useful Improvement in Envelop - Machines, of which the following is a specification, accompanied by drawings forming a part of the same, in which—

10 Figure 1 represents a side elevation of so much of an envelop machine as is necessary to illustrate the nature of my present invention. Fig. 2 is a top view of the same. Fig. 3 is a rear view of a portion of the machine employed for applying transparent strips or patches to the envelop blank. Fig. 4 is a top view of the reservoir for holding the transparent patches. Fig. 5 is a sectional view on line 5—5, Fig. 4. Fig. 6 is a sectional view on line 6—6, Fig. 4. Fig. 7 is a perspective view of one of the separators contained in the patch holding reservoir. Fig. 8 is a detail view of the device for registering the envelop blank on the pressing table, and 25 Fig. 9 is a view of the envelop blank having a transparent patch applied thereto and showing that side of the blank which is to form the inside of the folded envelop.

Similar letters and figures of reference refer 30 to similar parts in the different views.

My present invention relates to a machine for manufacturing what are known in the trade as "outlook envelopes" or envelopes having an opaque body with a transparent section or panel at that part of the envelop commonly occupied by the address. Envelops of this character are designed to be used with inclosures having the address suitably placed thereon to register with the transparent section of the envelop and form the address of the envelop. Such envelopes are manufactured by pasting a patch of transparent paper over an opening formed in proper position in the envelop blank.

45 The entire operation of applying the transparent patch to the body of the envelop has heretofore been done by hand, and it is the object of my present invention to provide mechanism for the application of the transparent patch to the body of the envelop by which the operation can be automatically and rapidly performed by mechanical means; and to arrange that the transparent patch shall be applied to the envelop blank during 50 the period intervening between the opera-

tions of gumming an envelop blank and folding the flaps of said blank as performed upon an envelop machine of the known type.

The mechanism embodying my present invention is designed to operate upon an envelop blank having an elongated piece cut from the body of the envelop at that part usually occupied by the address, and thereby forming an opening in the envelop, and my invention comprises means for applying adhesive material to the body of the envelop blank around the elongated opening; means for feeding the gummed envelop blank forward over a pressing table; means for registering the envelop blank on the pressing table; means for applying an elongated transparent patch to the body of the envelop blank slightly larger than the opening, so that the edge of the patch will overlap the gummed margin around the opening; means for applying pressure to the transparent patch to secure its firm adhesion to the body of the envelop blank; and means for removing the patched blank from the pressing table.

The combination of instrumentalities for 55 accomplishing the above mentioned operations automatically and by mechanical means in the order named, the combination of the above instrumentalities with an envelop machine for manufacturing a completed envelop, and such arrangement of parts of an envelop machine as may be necessary to apply a patch to an envelop blank between the operation of gumming an envelop blank and folding the flaps of said blank, 60 form the subject of my present invention.

In the accompanying drawings I have shown only such parts of an envelop machine as are necessary to clearly set forth the construction and operation of mechanism for carrying out my present invention, the remaining parts of the envelop machine as shown in the present instance having been fully described in Letters Patent of the United States, #401,462, issued to A. A. Rheutan, April 16, 1889. I do not confine myself, however, to any particular mechanism for affixing the patch; I have shown means for accomplishing this result in combination with the operation of an envelop machine, during the period intervening in such operation between gumming the envelop blank and folding the flaps of said blank, and any means of so doing would come within the spirit of my invention.

Referring to the accompanying drawings 1 denotes the framework of the machine, 2 the feeding table upon which a pile of envelop blanks 3 are supported in position to be 5 gummed. One of these envelop blanks is represented in top view as it lies upon the feed table and it comprises a seal flap 3¹, back flap 3² and end flaps 3³, 3³, which are folded over the central or body portion in the usual 10 well known manner to form an envelop. The central portion of the blank is provided with an elongated hole 3⁴, in that part of the blank usually occupied by the address.

In Fig. 9 the envelop blank is represented 15 with a transparent elongated patch 4 slightly larger than the hole 3⁴ which is pasted upon the body of the envelop by the mechanism forming the subject of my present invention. Gum is applied in a narrow strip around the 20 hole 3⁴ of the topmost blank in the pile 3, by means of a gumming die 5, which with a gumming die 6 is attached to a vertically reciprocating spindle 7, to which motion is given at the proper time by means of a 25 cam not shown, and connected operating mechanism. Gum is applied to the under surface of the gumming dies 5 and 6, when in their elevated position, by means of a traversing gum roll 8, which receives a coating 30 of gum at one end of its travel from a gumming roll 9, rotating in contact with a gumming roll 10, which is partially immersed in adhesive material contained in a gum box 11. The gumming dies 5 and 6 in their descent 35 35 apply gum in a narrow strip around the hole 3⁴ and also to the rear edge of the blank, causing the gummed blank to be lifted by the adhesion of its gummed surface as the dies move upward. The raised rear edge of 40 the blank is then seized by a hinged gripper 12 upon a carriage 12¹ and drawn backward toward the rear of the machine upon a table 13, and beneath horizontal guide bars 14, in position to be engaged by pawls 15, 15, 45 which hold the blank from being returned at the next forward movement of the carriage. At the next rearward reciprocating movement of the carriage, the envelop blank held by the pawls 15, is engaged by projecting 50 spurs 16, in position to be again retained by the pawls 17 at the next forward movement of the carriage. At the next succeeding rearward movement of the carriage the blank in its second position is engaged by hooks 18 55 and carried forward beneath a reciprocating plunger 19, by which it is pushed downward through a rectangular hole in a creasing plate 20 upon a folding bed, where its flaps are folded over by hinged folders, two of which 60 are represented at 21, Fig. 1. These operations and the mechanism by which they are performed, with the exception of the gumming die 5, are fully shown and described in the Letters Patent to Rheutan, above referred to, and form no part of my present in-

vention, the only addition I make to the gumming, carrying, and folding mechanism in carrying out my invention on a Rheutan envelop machine consists in the gumming die 5, shown in end view in Fig. 1, and in top view in Fig. 2, and designed to apply a narrow strip of gum around the hole 3⁴ which has been previously formed in the envelop blank.

While the envelop blank with gum applied 75 around the hole 3⁴ dwells in its second position of rest and retained by the pawls 17, I apply thereto the transparent patch 4, preferably shaped to correspond with the shape of the hole 3⁴, but slightly larger so as 80 to overlap the envelop blank as indicated by the narrow space 22, Fig. 9, and I accomplish this result as hereinafter described. Beneath the envelop blank 24 and arranged to support the same, I place a pressing table 85 23, Fig. 3, sufficiently firm to resist the downward pressure required to firmly attach the transparent patch to the envelop blank. Above the pressing table 23 is a vertically reciprocating patch-holder 25, consisting of 90 an iron receptacle open on its upper and lower sides, and provided at each end with vertical guide bars 26, 26, adapted to slide vertically in fixed ways 27 in the ends of brackets 28, attached to a cross bar 29, 95 which is supported at its ends by posts 30 erected on the framework of the machine.

Recessed in the inner wall of the patch-holder 25 are a series of separators 31, one of which is shown in perspective view in Fig. 100 7. Each separator consists of a metal bar provided at the lower end with inward projections or toes 32 adapted to extend beneath and support a series of patches held in the patch-holder as indicated by the broken 105 lines 33, Fig. 6. Held in circular holes in the wall of the patch-holder are a series of pins 34, provided with shoulders 35, against which spiral springs 36 are arranged to bear 110 to press the pins downward until their downward movement is limited by a cotter pin 37. The pins 34 are arranged in pairs, two on each side of the patch-holder, and their lower ends are connected by a notched plate 115 38 normally projecting beyond the lower end of the patch-holder, but capable of being forced upwardly into a recess 39 in the lower edge of the patch-holder. The guide bars 26 of the patch-holder are provided at their upper ends with studs 40, which are connected 120 by links 41, with arms 42, carried upon a rocking shaft 43, carrying a radial arm 44, to the outer end of which is pivoted a link 45, carrying at its lower end a cam roll 46, which is held in contact with a cam 47, carried upon 125 the cam shaft 48, the cam roll being held in contact with the cam 47 by a spiral spring 49, causing a rocking motion to be imparted to the rock shaft 43 at the proper time to carry the patch-holder 25 down and bring 130

the lowermost patch into contact with the gummed surface of the envelop blank around the hole 3⁴.

Inclosed in the patch-holder and above the series of patches, is a follower 50 attached to a stem 51 which is pivoted at its upper end to a lever 52. The lever 52 is pivoted at one end at 53 to a fixed bracket 54, and its opposite end is bifurcated and provided with a pivotal pin 55, which extends through a slot 56 in the upper end of a link 57, which is pivoted at its lower end to an arm 58, carried by a rock shaft 59, journaled in fixed brackets 60, 60, and carrying an arm 61, to the end of which is pivoted a link 62, carrying a cam roll 63, which is held in contact with a cam 64, on the shaft 48, by a spiral spring 65, by which at the proper period a rocking motion is imparted to the shaft 59 to carry the follower 50 downward and apply a pressure to the patches as hereinafter described.

Attached to the extended ends of the pin 55 are spiral springs 66, having their opposite ends attached to the radial arm 58, so that the pin 55 is normally held at the lower end of the slot 56. The reciprocating motion of the carriage 12¹ is accomplished by means of a lever 67 connected by a link 68 with the carriage at its upper end, with its lower end attached to a rock shaft 69, which is provided with an arm 70, connected by a link 71, with an eccentric strap 72, on an eccentric 73, on the cam shaft 48. The envelop blank is held in proper registration on the pressing table 23, by a device shown in Figs. 3 and 8, and consisting of a short rock shaft 74 journaled beneath the pressing table 23, and provided with a pair of radial arms 75, to the free ends of which are adjustably attached registering pins 76, capable of a vertical sliding movement in lugs 77, as the shaft 74 is rocked. The shaft 74 is also provided with a third radial arm 78 extending obliquely downward, carrying on its free end a roll 79, in the path of an arm 80, carried by the carriage 12¹, and arranged to contact at the proper period with the roll 79 and rock the shaft 74, to carry the registering pins 76 above the upper surface of the pressing table 23 and engage the rear edge of the envelop blank and hold it in proper position on the pressing table, with the opening 3⁴ in proper registration with the patches supported above it in the patch-holder 25. The inner surfaces of the separator bars 31 are provided with triangular teeth 81, adapted to scrape the edges of the patches as they are moved down in the patch-holder and prevent them from clinging to each other. The desired pressure of the teeth 81 against the edges of the patches is secured by means of an adjusting screw 82, Fig. 6, held in the patch-holder and arranged to bear against the separator bar and push it inward against the

patches. The separator bars are held in place in the patch-holder by means of retaining screws 83 which pass through a hole in the patch-holder and enter a screw threaded hole 84 in the separator bar.

The operation of the above described mechanism for applying patches to the envelop blank is as follows:—A gummed envelop is brought into the position of the blank 24, Figs. 2 and 3, by the rearward movement of the carriage 12¹, with the body of the envelop blank over the pressing table 23 against the registering pins 76. During the dwell of the blank in this position or during the return forward movement of the carriage, the patch-holder 25 is carried down by the action of the cam 47 and spiral spring 49, to bring the lowermost patch in the holder into contact with the gummed surface of the envelop blank surrounding the hole 3⁴. The patch-holder is held at the downward end of its movement for a short period by a short concentric section 85 of the cam 47 before it is again raised to its normal position, in which it is held by the concentric section 86 of the cam 47. The cam 64 is suitably shaped to allow the spring 65 to move the follower 50 from its elevated position, first gradually downward following the patches in the patch-holder 25, and when the patch-holder has reached its lowest position with a patch in contact with the envelop blank, the depressed section 87 of the cam 64 allows the spring 65 to bring the follower down with a quick and sudden movement, thereby imparting a blow to the patches in the patch-holder with sufficient force to cause the firm adhesion of the lowermost patch to the gummed surface of the envelop blank, when the cam 64 raises the follower in advance of the upward movement of the patch-holder and holds it in its elevated position by the concentric section 88 of the cam 64. The adhesion of the lowermost patch to the gummed surface of the envelop blank is sufficient to remove the patch from the patch-holder past the toes 32 of the separators. The envelop blank with a patch 4 applied thereto covering the hole 3⁴, as represented in Fig. 9, is then moved rearward by the next backward movement of the carriage by the engagement of the hooks 18, Fig. 1, carrying the blank beneath the plunger 19, by which it is pushed downward through the creasing plate upon the folding bed in the usual manner in envelop machines.

Although I have shown and described a patch applying mechanism in connection with the envelop machine described in Letters Patent of the United States #401,462, I do not confine myself to this particular type of envelop machine. Any type of envelop machine preferably one in which a dwell can be given to the envelop blank between the gumming and folding mechanisms, is adapt¹

ed to the application of my patch applying mechanism.

The patch holding receptacle, pressing table and follower for applying pressure to the patch, with their connected actuated mechanisms may be employed independently of the gumming and folding mechanisms; the operations of gumming around the opening in the envelop blank, and of folding the blank 10 into an envelop being performed by independent mechanisms, if so desired.

So far as I am aware it is broadly new to apply a patch to the opening in an envelop blank by mechanical means, and to combine 15 a patch applying mechanism with an envelop machine, so as to affix the patch to the envelop blank between the operations of gumming the blank and of folding the flaps of the envelop, and I do not wish to confine 20 myself to the above specific construction and arrangement of the mechanism for applying a patch to an envelop blank and for pressing their overlapping surfaces together, as modifications in the various details of construction 25 and arrangement may be made without departing from the scope of my present invention.

What I claim as my invention and desire 30 to secure by Letters Patent is:—

1. In an envelop machine, the combination 35 of the following instrumentalities, means for applying gum around an opening in an envelop blank, means for feeding the gummed blank to a pressing mechanism, means for applying a patch to the envelop blank to cover the opening, a pressing mechanism comprising means for applying pressure to the overlapping surfaces of the patch and blank, means for feeding the patched 40 blank to a folding mechanism, and means for folding the blank.

2. In an envelop machine, the combination 45 of a feeding table for supporting a pile of envelop blanks, a reciprocating gumming die for applying gum around an opening in the uppermost blank in said pile, means for feeding the gummed blank to a pressing table, means for applying a patch to the envelop to cover the opening, and means acting 50 coincidently with the application of the patch to the blank, for firmly uniting the patch to the blank.

3. In an envelop machine, the combination 55 of a feeding table for supporting a pile of envelop blanks, a reciprocating gumming die for applying gum around an opening in the uppermost blank, means for feeding said blank to a pressing table, means for applying a patch to the envelop blank to cover the 60 opening, means, acting coincidently with the application of a patch to the blank, for firmly uniting the patch to the blank, and means for the withdrawal of said blank and patch from said pressing table.

4. The combination with a feeding table

for supporting a pile of envelop blanks, means for applying gum around an opening in the uppermost blank, a pressing table for supporting said blank, a reciprocating carriage for feeding said blank to said pressing table, means for controlling the position of said blank on said pressing table, means for applying a patch to the gummed surface of said blank while on said pressing table, and means acting coincidently with said application of said patch to said blank for firmly uniting said patch to said blank.

5. In an envelop machine, the combination 70 with mechanism for gumming an envelop blank around an opening therein, mechanism for folding the blank and means for feeding the blank from the gumming to the folding mechanisms with an intervening dwell of the blank, of mechanism interposed between the gumming and folding mechanisms for applying a patch to the blank covering 75 the opening therein.

6. The combination with mechanism for gumming and folding an envelop blank, of means for feeding the blank from the gumming to the folding mechanisms with an intervening dwell of the blank, a pressing table adapted to support the blank during its intervening period of dwell and mechanism for securely affixing a patch to said blank during 80 its intervening period of dwell.

7. The combination with mechanisms for gumming and folding an envelop blank, of a pressing table interposed between said gumming and folding mechanisms, means for feeding a blank from the gumming to the folding mechanisms over said table with a period of dwell therein, means for registering the blank on said table, means for applying a patch to the blank during its period of dwell, and means for applying pressure to 100 the overlapping surfaces of the patch and blank.

8. In a mechanism for attaching patches to envelop blanks, having openings therein, the combination of a support for an envelop blank, a gumming die for applying adhesive material around said opening, a receptacle for holding patches for covering said opening, an envelop support beneath said receptacle, means for feeding the gummed blank from beneath the gumming die to a position beneath the patch receptacle, means for imparting a downward movement to said receptacle to carry a patch into contact with the gummed surface of the envelop blank, a follower for pressing the patch upon the blank and means for imparting a downward movement to said follower independently of the movement of the receptacle.

9. In a mechanism for attaching patches to the gummed surface of an envelop blank, the combination of a pressing table for supporting an envelop blank, with an opening in said blank having gummed edges, a carriage 125

for carrying said blank across the upper surface of said pressing table, means for actuating said carriage whereby a period of dwell is given to said blank upon said table, movable pins for registering said blank upon said table, means for carrying said pins into and out of the path of said blank, a patch holding receptacle, means for moving said receptacle to carry a patch into contact with the blank, 10 means acting coincidently with the movement of said receptacle for firmly affixing said patch to said blank, and means for separating the lowermost patch as it is brought into contact with the gummed surface of said 15 blank.

10. In a mechanism for attaching a patch to an envelop blank, the combination of a support for the blank, vertical guides above said support, a receptacle for patches moving in said guides, a rock shaft, radial arms carried by said rock shaft and pivotally connected with said receptacle, an arm on said rock shaft, a link pivoted to said arm, a cam roll carried by said link, a cam for controlling 25 the movement of said cam roll, and a spring for holding the cam roll in contact with the cam.

11. In a mechanism for attaching a patch to an envelop blank, the combination of a support for the blank, a receptacle for patches, means for moving said receptacle downward to carry a patch into contact with the blank, a follower, means for moving said follower independently from said receptacle 30 and means for imparting an additional and sudden pressure to said follower when the receptacle has completed its downward movement.

12. In a mechanism for attaching a patch to an envelop blank, the combination with a support for the blank, a reciprocating patch holder, of movable plates in the lower edge of the patch holder, whereby the blank is retained on its support as the patch holder is raised upward. 45

13. In a mechanism for attaching a patch to an envelop blank, the combination with a support for the blank and a reciprocating patch holder, of means for separating the lowermost patch consisting of separator bars 50 provided with inward projections or toes at their lower ends and with teeth above said arms in contact with the patches.

14. In an envelop machine, the combination of the following instrumentalities, means for applying gum around an opening in an envelop blank, means for feeding the gummed blank to a pressing mechanism, means for applying a patch to the envelop blank to cover the opening, a pressing mechanism for 60 securely affixing said patch to said blank, and means for folding the flap of the envelop.

15. The combination with mechanism for gumming an envelop blank around an opening therein, mechanism for folding the flaps 65 of said blank and means for feeding the blank from the gumming mechanism to the flap folding mechanism, of mechanism interposed between the gumming mechanism and flap folding mechanisms for applying a patch to 70 the blank to cover the opening therein.

Dated this third day of July 1903.
